UNITED STATES PATENT OFFICE.

FRANCIS ALVIN REECE AND LUCION TELL COVENTRY, OF SEDRO-WOOLLEY,
WASHINGTON.

BURGLAR ALARM.

Application filed April 25, 1925. Serial No. 25,921.

To all whom it may concern:

Be it known that we, FRANCIS ALVIN REECE and LUCION TELL COVENTRY, citizens of the United States, and residents of Sedro-Woolley, in the county of Skagit and State of Washington, have invented certain new and useful Improvements in Burglar Alarms, of which the following is a specification.

Our present invention relates generally to 10 burglar alarms, and more particularly to mechanical cartridge firing apparatus applicable to doors and windows in such arrangement that when the door or window is opened, the cartridge will be fired, and our 15 object is the provision for this purpose of a simple inexpensive apparatus which will be positive and unfailing in its action, as well as one which may be mounted and manipulated so as to avoid effective movement 20 of its parts in case of approach to the door of one who is warranted to enter and properly equipped for that purpose.

In the accompanying drawing which illustrates our present invention and forms a 25 part of this specification,

Figure 1 is a front elevation illustrating the practical application of our invention,

Figure 2 is a side view partly broken away and in section,

Figure 3 is a vertical longitudinal section taken centrally through the device with the parts in the actuated position,

Figure 4 is a horizontal section taken substantially on the line 4-4 of Figure 1,

Figure 5 is another horizontal section taken substantially on the line 5-5 of Figure 1,

Figure 6 is a front elevation showing the parts arranged with an actuating member adapted to be shifted out of effective position by means of a key, and

Figures 7 and 8 are perspective views respectively of the actuating member shown in Figure 6, and the key for moving said member to inactive position.

Referring now to these figures, our invention proposes an apparatus in which a bolt 10 is mounted lengthwise of a bracket 11, to shift in the direction of its length and to rotate in said bracket, the latter having for 50 this purpose spaced portions with guide apertures for the bolt 10, the space between which portions exposes a part of the bolt. In its exposed portion the bolt has an arm fixed therethrough to outstand substantially 55 therefrom at one side as indicated at 12,

and this arm serves as an abutment for one end of an actuating spring 13 coiled around the bolt and abutting at its opposite end one end 14 of the bracket 11 beyond the latter of which the adjacent end of the bolt 10 has 60 an angular extension or arm 15.

The opposite end of the bolt 10 within the bracket 11 is formed with an endwise projecting stud 16 constituting a firing pin, and this end of the bolt is movable in a guide 65 opening 17 of the bracket and in its inner position to which it is forced by the actuating spring 13, the last mentioned end of the bolt 10 projects into a transverse bore 18 of the bracket 11 which is preferably squared 70 for the movable reception of a rectangular elongated cartridge block 19. This cartridge block has a series of openings each adapted to receive therein a cartridge 20, and the block being shiftable in the bore 18 of the 75 bracket is thus movable to bring the cap carried or flanged end of each cartridge in alinement with the bolt 10. The cartridge block is moreover provided on its front face with a series of recesses 21, one opposite 80 each of the cartridge receiving apertures, each of which recesses is adapted for engagement by the angularly bent engaging portion 22 of a spring wire holder 23, one end of which is anchored in the front face of 85 the bracket 11 and the opposite end of which forms a handle whereby this locking wire may be readily flexed for movement out of any one of the recesses 21 when the cartridge block is shifted to bring a fresh cartridge 90 into firing position, or in other words, into alinement with the firing bolt 10.

The bracket 11 has extensions 24 and 25 at its opposite ends apertured for the reception of screw fasteners 26, whereby it may 95 be secured to a door or window, and this bracket is further provided with side walls 27 at opposite sides of the exposed portion of the bolt 10, recessed to form shoulders 28 at opposite sides against which a laterally 100 projecting latch pin 12 of the firing bolt 10 is movable when the bolt has been drawn outwardly and turned so that its angular end 15 projects laterally either to the right or left of the bracket 11, as the case may be. 105

In operation, the bracket 11 is mounted in vertical position upon a door frame 29 as in Figure 1, where it is to be used in connection with a door, adjacent to and parallel with the free edge of the door 30 and 110

so spaced therefrom with the free end of the angular extension 15 of the firing bolt slightly overlaps the free edge of the door 30. Thus when the door is opened its free edge will engage the arm 15 and the latter will be swung to a sufficient extent to rotate the bolt 10 and shift its latching arm 12 out of engagement with the shoulder 28, thus releasing the firing bolt for lengthwise movement under actuation of its spring 15 so that its firing pin 16 will engage and explode a cartridge 20 alined at that time with the firing bolt.

Where the apparatus is used in connection with a window, it is mounted in connection with one of the sashes, for instance, the upper sash so that the end of the section 15 will normally overlie the upper edge of the lower sash. Thus when either the upper sash is lowered or the lower sash is raised, actuation of the apparatus to the desired end will take place.

Where the device is desired for use in such manner that its action may be prevented by those entering the door who have a right to do so, it may be mounted as in Figure 6 with the end of the extension 15 of the firing bolt terminating short of the edge of the door casing 31, a key controlled actuating arm 32 being mounted transversely across that portion of the door 33 adjacent to its free edge, and being normally extended beyond the door edge in line with the bolt extension 15 for actuation of the latter. This arm 32 has its lower edge notched at 34 intermediate its ends as shown in Figures 6 and 7 and so positioned as to overlie the key opening 36 of the door. Screws or like members 35' and 37' are set into the door through slots 35 and 37 of the arm so as to hold the latter slidably in a horizontal plane. Thus if the door is forced open the cartridge firing apparatus will be actuated. On the other hand, the entrance of one entitled to enter the door is provided for by virtue of a key 38 as shown in Figure 8, which may be extended through the key opening so that its

shank 39 in the rotation of the key will swing into the notch 34 and engage and move the actuating arm 32 lengthwise so as to shift its outer free end away from the angular arm 15 of the firing bolt. In this way the door may be opened without actuating the cartridge firing mechanism.

Our invention presents an apparatus which is thus not only simple and inexpensive considering the results achieved, but one capable of use in connection with doors or windows and in various positions for warning in the event of burglarious or unwarranted entry.

We claim:—

1. In an alarm including a spring actuated firing bolt, and a bracket in which said bolt is controlled and actuated, a cartridge holder having a lengthwise series of cartridge chambers, said bracket having an opening through which the holder is movable to successfully aline its cartridge chambers with the firing bolt, and means on the bracket and cooperating therewith and with the holder to prevent accidental displacement of the holder when one of its said chambers is alined with the firing bolt.

2. In an alarm including a spring actuated firing bolt, and a bracket in which said bolt is controlled and actuated, a cartridge holder having a lengthwise series of cartridge chambers, said bracket having an opening through which the holder is movable to successfully aline its cartridge chambers with the firing bolt, said bracket also having a slot through its wall opposite the holder receiving opening, and said holder having a recess in one face opposite each of its chambers, and a spring retaining member mounted on the bracket and having a portion thereof normally extending through the slot of the bracket and into one of the holder recesses whereby to support the holder against accidental displacement.

FRANCIS ALVIN REECE.
LUCION TELL COVENTRY.
